UNITED STATES PATENT OFFICE.

ARTHUR L. HALLIDAY, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 12,200, dated March 29, 1881.

Application filed February 3, 1881. Term of patent 3½ years.

To all whom it may concern:

Be it known that I, ARTHUR L. HALLIDAY, of the city of New York, county of New York, and State of New York, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The figure I is a cluster of leaves, from which projects a branch bearing three flowers shaped like star-flowers. This figure I overlaps a figure, F, resembling a large, irregular leaf, with dotted figures thereon, this leaf having also upon it a figure, g, consisting of three pointed leaf-like figures.

The figure h consists of a bunch of leaves, from which projects a bunch of flowers consisting of a bud and two open flowers. This figure h overlaps the figure E, resembling an irregularly-shaped serrated leaf. The figure d is a twig, with leaves thereon, and overlaps the figure C, which is a large, flat, serrated leaf with ornamentation thereon.

The figure f consists of a bunch of oblong leaves with a branch projecting therefrom, on which are found flowers and buds.

The figure k is also a branch, with circular leaves and open flowers thereon, overlapping the figure G, which is another large serrated leaf with a dotted ornamentation upon it.

The figure O resembles a cluster of sharp, slim leaves, with small drooping flowers between them, and connects the figure G with the figure m—another serrated, ornamented flat leaf.

The figure H is a cluster of slim pointed leaves, interspersed with flowers, and projecting over a flat serrated leaf.

The figure J consists of oval leaves, with flowers on long stems projecting therefrom.

The figure j consists of a small leaf placed in the center of a large serrated and ornamented leaf, which is partly overlapped by

the figure D, consisting of a bunch of triangular leaves with flowers projecting therefrom.

50

The figure i consists of small pointed leaves with pendent flowers, and somewhat resembles the figure O.

The figure l is another large, serrated, ornamented leaf, overlapped by the figure K—a circular serrated leaf with ornamentation similar to that of the figures C and m, and having overlapping one side the figure a, consisting of a twig with leaves and flowers thereon, while the other side is overlapped by the figure n—a branch with flowers and pointed leaves, and which connects the figure K with the serrated circular leaf-like figure B.

The whole effect is that of clusters of leaves with projecting flowers, and of twigs and branches with flowers thereon, scattered irregularly over a background consisting of large irregular serrated leaves, whose interstices are filled in by varied checkered patterns.

I claim—

1. The design for carpets, consisting of the figure I, substantially as shown.
2. The design for carpets, consisting of the figure F, substantially as shown.
3. The design for carpets, consisting of the figures I, F, and g, substantially as shown.
4. The design for carpets, consisting of the figure h, substantially as shown.
5. The design for carpets, consisting of the figure C, substantially as shown.
6. The design for carpets, consisting of the figures h and E, substantially as shown.
7. The design for carpets, consisting of the figure d, substantially as shown.
8. The design for carpets, consisting of the figure k, substantially as shown.
9. The design for carpets, consisting of the figure f, substantially as shown.
10. The design for carpets, consisting of the figure O, substantially as shown.
11. The design for carpets, consisting of the figures k and G, substantially as shown.
12. The design for carpets, consisting of the figure m, substantially as shown.
13. The design for carpets, consisting of the figure J, substantially as shown.

14. The design for carpets, consisting of the figure *a*, substantially as shown.
15. The design for carpets, consisting of the figure *n*, substantially as shown.
- 5 16. The design for carpets, consisting of the figures *h*, *B*, and *F*, substantially as shown.
17. The design for carpets, consisting of the

figures *I*, *F*, *g*, *h*, *H*, *B*, *E*, *C*, *d*, *f*, *G*, *k*, *O*, *j*, *D*, *m*, *J*, *a*, *l*, *i*, *K*, and *n*, substantially as shown.

ARTHUR L. HALLIDAY.

Witnesses:

HENRY F. HOLDEN,
WILLY G. E. SCHULTZ.
